FOLDING SHELF FOR BED CLOTHES

William M. Emery, New Providence, N.J., assignor to Better Sleep Mfg. Co., Berkeley Heights, N.J., a corporation of New Jersey

Filed July 29, 1963, Ser. No. 298,276

3 Claims. (Cl. 5—319)

My present invention refers to a folding shelf for bed clothes which is conveniently placed to support excess covers, blankets, bed spreads, etc. above the foot of the bed within easy reach of the sleeper. Just by sitting up in bed your fingertips will reach the extra blanket needed in the early morning hours whereas many other shelves, etc. necessitate getting out of bed to secure extra covering. Also the shelf may be placed between the sheets to free the feet of the weight of all coverings or between the top sheet and the blankets in which case sheet contact is retained which some prefer while eliminating the burden of the heavier covers on the feet. My shelf is composed of sections mounted on support arms which can be collapsed flat from their elevated vertical position by crossing them. When this is done the shelf wings pivot on the overhanging portion of the support arms so that they flatten invisibly and unobtrusively under the covers against the mattress top when the bed is made.

Reference is made to my Patent #2,710,414.

Objects of my present invention are to provide certain new improvements as the result of considerable inventive thought over the years that only currently has brought fruit although I have recognized the need for considerable time, and have searched for a practical solution that would not sacrifice certain essential original features. So objects include reducing the tendency of the elevated covers to sag between the arms by providing extended shelf-like elements pivotally mounted on the arms to turn on horizontal axes. This increases the spread of the shelf, reduces sag and allows the arms and the shelves to flatten against the top of the mattress when the bed is made. Another object is to provide a thin pivotal protection for the forward pointing ends of the support arms so that if the ends are kicked accidentally by a tender foot, the arm end cannot injure the skin or bruise the foot, and more particularly, to do this without interfering with the arm folding invisibly flat when the bed is made. Another object is to provide a base with greater stability with a minimum amount of weight increase. The successful accomplishment of these and other objects will be obvious from the specification and claims hereafter and from the drawings in which—

FIGURE 1 is an orthographic projection showing my folding sectional shelf in a covers supporting position at the end of a conventional footless bed.

FIG. 2 is an elevation viewed from the foot end of the bed of FIG. 1.

FIG. 3 is a sectional view from 3—3 of FIG. 2,

FIG. 4 is an elevation viewed like FIG. 2 but the arms and the shelf sections lowered flat to mattress top,

FIG. 5 is a fragmentary bottom view of FIGS. 2 or 3, and

FIG. 6 is a fragmentary view showing one of the pivotal shelves and its mounting.

FIG. 1 shows a conventional bed frame and springs 19 with a conventional mattress 20 thereon covered conventionally with a bed sheet or sheets. The convenient location of the extra bed covers when elevated over the foot of the bed is indicated in broken lines.

Shown in several views are two C shaped support arms 21 and 22 comprising an end 24, an upper overhanging horizontal section 23, a curved section 25, a substantially normally upright section 26, an offset sec-

tion 27 and a lower horizontal section 28 which has therein a shoulder 29.

FIGS. 2, 3, and 4 show a sheet metal base 30 which has less width than the bed and is held by the weight and stiffness of the mattress between the mattress 20 and the bed frame 19 or box spring or other equivalent. The bend 31 of base 30 has two end holes which mount two stop rivets 32 and two other holes 33 that pivot horizontal section 23 of arms 21 and 22. Base 30 also has offset ears 34 that pivot the ends of sections 28 so that support arms 21 and 22 are pivoted in a common horizontal plane for movement about substantially horizontal and parallel axes by holes 33 and ears 34 in base 30. To provide, without tools, quick attachment and detachment of the arms 22 and 23 to and from the base 30 bent spring edge 35, a continuation of bend 31, snaps in behind shoulder 29 to hold sections 23 of arms of 21 and 22 from coming out of base 30. Base 30 is extended beyond the ends of sections 28 at 36 to provide extra stability and the extended edge is bent downward at 37 to discourage sliding of the base.

Identical reversible shelves 40 are pivotally mounted to turn on the upper overhanging horizontal sections 23 of arms 21 and 22. As shown in FIGS. 2, 3, 4 and 6 these shelves consist of normally horizontal fins 41 extending laterally from a tubular center 42 into which upper sections 23 of arms 21 and 22 are loosely inserted. The curve of section 25 stops the shelves 40 from sliding too far horizontally on to the radius 25 and elastic rubber band or plastic sleeve or retaining ring 43 prevents the shelf from moving in the opposite direction off the end 24 of section 23. The shelves are indented at 44 to avoid rotary interference with curve 24 when it pivots and is likewise indented at 45 so that the shelves extend beyond the end or point 24 of upper arm section 23 so as to prevent injury to the foot of the sleeper if the foot accidentally strikes or kicks the end which has been a medical criticism of my original invention. The indenting of both ends at 44 and 45 also allows of shelves of maximum length allowable without increasing the overall dimension.

Comparison of FIGS. 2 and 3 shows that the relative pivotal movement of shelves 40 turning on upper sections 23 of arms 21 and 22 to be about 90° from their raised position in order to lay unobtrusively and invisibly flat against the top of the mattress under the covers when the arms 21 and 22 are lowered by crossing them when the bed is made as shown in FIG. 4.

Essential and unique features of my invention include the pivotal relationship between the shelves and their support rods which allow said 90° or more of movement there between. Thus flat thin sectional shelves are provided, and protection for the feet against injurious contact with the support rod ends 24 is secured by, a single means without bulbous ends or fixed attachments which would interfere, because of said 90° movement with the folded arms, with the shelves lying flat against the mattress top which is most essential for consumer acceptance.

In use, assuming that the bed has been made with arms 21 and 22 crossed and the shelf sections flat against the mattress top, first the bed spread is folded back on the foot of the bed in quarters and then the other covers are folded individually back in thirds so their top edge is towards the head of the bed. With the covers thus folded and positioned it is easy to reach down to the foot of the bed and uncross the arms 21 and 22 spreading them to their more vertical position thus raising the shelf segments 40 which simultaneously lifts the covers in place without materially disturbing them. They are now within easy reach of the sleeper and his bed seems larger because it is not hampered by folded covers resting on and adjacent to his feet.

Accordingly, I claim:

1. A folding shelf for bed clothes comprising a base of lesser width than a standard mattress and suitable for positioning under the foot of a mattress, two C shaped arms pivotally mounted with substantially parallel and horizontal axes substantially within the plane of said base, and protruding from a common edge thereof, other portions of said C arms extending upward and around the end of said mattress terminating in overhanging ends generally substantially parallel to said axes, and shelf sections individually mounted to pivot and being freely balanced on said overhanging ends in a manner avoiding instability or unstable equilibrium, said pivotal mounting of the C arms in said base and pivotal mounting of said shelves on said arms being such that said shelves may be lowered flat against said mattress top when the bed is made.

2. A folding shelf for bed clothes comprising a base of lesser width than a standard mattress and suitable for positioning under the foot of a mattress, two C shaped arms pivotally mounted with substantially parallel and horizontal axes substantially within the plane of said base, and protruding from a common edge thereof, other portions of said C arms extending upward and around the end of said mattress terminating in overhanging sections generally substantially parallel to said axes, and individual shelf wings pivotally mounted on each section with said sections as axes, said shelf wings including fins extending laterally from said axes, said shelf fins being indented on

5

one side adjacent to said axes by suitable curving to allow pivotal movement free of interference with said curved portion on one end of said shelf fins and other indentation on the opposite side of said fins adjacent to said axis with projection therefrom to guard said end from injurious contact by a user.

10

3. A folding shelf for bed clothes comprising a base of lesser width than a standard mattress and suitable for positioning under the foot of a mattress, two C shaped arms pivotally mounted with substantially parallel and horizontal axes substantially within the plane of said base, and protruding from a common edge thereof, other portions of said C arms extending upward and around the end of said mattress terminating in overhanging sections substantially parallel to said axes, individual shelf wings pivotally mounted on each of said sections with said sections as axes, said shelf wings including fins extending laterally from said axes, said fins extending beyond said end to guard said end from injurious contact with user and said arms being adapted to raise said sections above the foot of a bed also operative to lower said fins flat against said bed when the bed is made.
